ABSTRACT OF THE DISCLOSURE

Apparatus and methods are disclosed for felting of textile fabric webs by the action of barbed felting needles so as to produce linear fiber fascicles extending primarily within the thickness of the web. Included are disclosures of a curved felting needle, methods and apparatus for effecting entry and emergence of a felting needle from the same surface of a textile web during each needle penetration, and methods and apparatus for imparting overlapping oscillatory increments of movement to felting needles resulting in an increased degree of fiber concatenation.

This invention relates to the art of the integration or felting of textile fibers by the action of barbed felting needles, and more particularly, to novel and improved instrumentalities and apparatus for performing such felting operations as well as to the unique methods and processes by which such felting operations may be conducted and to the novel felted products which are attainable thereby.

When a web of loosely or randomly arranged fibers or two or more layers of fibers are penetrated by barbed felting needles, the resulting commingling and reorientation of the fibers can result in a compaction of the total web thickness, a union of two or more layers, and an increase in the cohesive strength of the web. The degree to which these results are obtainable depends in part upon the nature of the fibers being worked and to a large degree upon the instrumentalities and methods employed.

It is known in the art of felting to utilize straight barbed felting needles for concatenating the fibers of a textile workpiece by using plain reciprocation of the straight barbed needles through the workpiece either perpendicular to or at a slight angle to the workpiece surface.

Using this known arrangement, the needles in penetrating the workpiece, form holes through the workpiece which not only make the workpiece porous but are noticeable on the faces of the workpiece. It is also true of the known arrangement that the fibers of the workpiece are intercongregated by the action of the needle only in a direction substantially perpendicular to the workpiece surface i.e., directly through the workpiece, so that the intermingling of fibers will occur over a minimum distance. These factors of unidirectional fiber concatenation over a minimum distance together with the inherent formation of through holes seriously limit not only the degree of compaction which can be attained but also limit the degree of strength and cohesion which may be imparted to the web by the needling process.

It is an object of this invention to provide novel instrumentalities and apparatus for felting in which barbed felting needles will enter and emerge from the same face of a workpiece during each needle stroke.

Where the workpiece is maintained in planar disposition during the felting process, this invention comprehends

2

the use of an arcuate felting needle which is oscillatable about an axis corresponding to the center of curvature of the felting needle so as to enter and emerge from the same face of the planar workpiece. With this needle arrangement, through holes are avoided in the workpiece, the holes which are produced lie at such an acute angle to the surface of the workpiece as not to be apparent, and each needle passage, since it occurs primarily within the thickness of the workpiece extends over a far greater distance within the workpiece than in the case of the known straight felting needles thereby increasing the effectiveness of fiber intercongregation during each needle stroke.

In those instances in which manipulation of a workpiece in a non-planar path during the felting process would not be detrimental to the finished product, this invention provides for the use of straight felting needles arranged to enter and emerge from the same face of a workpiece as the workpiece is directed in an arcuate path.

It is also an object of this invention to provide novel methods of felting and the superior felted products attained thereby. The novel methods of this invention can utilize curved felting needles arranged to oscillate in paths which intersect angularly, and in addition can utilize such angularly arranged curved felting needles in combination with a conventional felting operation using straight felting needles passing through the workpiece. The advantage of these novel methods resides in the superior strength and cohesion of resulting felted product attained by orientation of the fibers in diverse directions. Where the angularly arranged curved felting needles are combined with the conventional straight felting needles an advantageous three dimensional fiber orientation can be attained in three substantially perpendicular planes.

In instances in which only curved felting needles are employed the path of needle reciprocation may be arranged so as to pass close to but avoid completely one surface of the textile fiber web being needled. In this manner the integrity of the avoided surface can be maintained and, for instance, the color or type of fiber appearing at the avoided surface will not be mixed with or visibly influenced by the remaining fibers of the web.

Yet another object of this invention is to provide a novel mechanism for actuating barbed felting needles in which the needles rather than being moved in plain or conventional reciprocating fashion are imparted an endwise reciprocation impressed with a higher frequency endwise vibration such that each needle stroke comprises a series of overlapping oscillatory increments. It has been found that this novel mode of felting needle actuation greatly reduces fiber breakage in the needling process while materially increasing the degree of fiber intercongregation with the resulting advantage of increased strength and cohesion in the felted product.

With the above and additional objects and advantages in view as will hereinafter appear, this invention is illustrated in the accompanying drawings in which:

FIG. 1 represents a diagrammatic elevational view of an apparatus embodying the principles of this invention and utilizing separate banks of straight and curved felting needles.

FIG. 2 is a cross-sectional view of a modified needle and web supporting arrangement in which straight needles and curved web supporting surfaces are employed with the needles illustrated at the completion of a work pene-

tration stroke showing that the needles will enter and emerge from the same side of the fiber web,

FIG. 3 is a cross-sectional view of a modified needle and web supporting arrangement in which curved needles and curved web supporting surfaces are employed,

FIG. 4 is a perspective view of a curved felting needle of this invention,

FIG. 5 is a cross-sectional view of a modified needle and web supporting arrangement in which both curved and straight felting needles are employed to produce three dimensional felting,

FIG. 6 represents a top plan view of the needle arrangement of FIG. 5,

FIG. 7 is a perspective view of a portion of fabric web which is being felted by a needle arrangement as illustrated in FIGS. 5 and 6 with two of the fabric edges illustrated in cross-section each taken along the direction of motion of one of the banks of curved needles,

FIG. 8 represents a cross-sectional view of a portion of fabric web comprising layers of fibers of two different colors which have been felted by an arrangement employing only curved felting needles, and

FIG. 9 is an enlarged cross-sectional representation of a textile web felted in accordance with this invention and illustrating the novel fiber orientation attained on one stroke of a needle having only one barb using the overlapping reciprocatory needle actuation of this invention.

Referring to FIG. 1 this invention is illustrated as applied to an organized machine capable of needling textile fabric webs as the web is passed along a supporting surface 11. The supporting surface 11 may be sustained by any conventional type of frame (not shown) relatively to a main drive shaft 12 from which the reciprocatory action of the felting needle and the feeding movements of the fabric web are derived.

A pulley 13 fast on the main drive shaft accommodates a belt 14 entrained on a pulley 15 carried on a counter-shaft 16. A crank pin 17 adjustably secured in a radial slot 18 in the pulley 15 is embraced by a connecting rod 19 pivotally connected as at 20 to an oscillatory arm 21 operatively associated with a one way clutch 22 which may preferably be of the sprag type. The one way clutch 22 is carried on a feed shaft 23 and serves to impart increments of turning movement in one direction to a fabric web feeding roller 24 on the feed shaft over which the finished fabric web is directed.

Indicated at 25 are additional fabric web feeding rollers opposed to the supporting surface 11. The feeding rollers 25 are each turned by a one way clutch 26 having an oscillatory arm 27 drivingly associated therewith. The arms 27 may be linked to the arm 21 for operation, or the arms 27 may be driven each by separate crank mechanisms from the main drive shaft 12.

Arranged between the work feeding rollers 25 is a needle board or crosshead 30 from which depends a multiplicity of straight barbed felting needles 31. Associated with the needle board or crosshead 30, is a depending bracket 32 to which is pivoted as at 33 a connecting rod 34 which embraces a crank pin 35 carried on a crank disk 36 fast on the main drive shaft 12. Rotation of the main drive shaft 12, therefore, will impart plain vertical reciprocatory movement to the straight felting needles 31 through apertures 37 aligned with the needles and formed in a pressure plate 38 positioned by conventional biasing mechanism (not shown) by way of pressure rods 39 at a selected distance from the supporting surface 11. The straight felting needles 31 may also reciprocate through apertures 40 aligned with the needles in the supporting surface 11.

Arranged between and parallel to the work feeding rollers 24 and 25 and above the work supporting surface 11 is a needle rock shaft 50 to which may be secured one or more needle clamps 51. The needle clamps 51 fixedly accommodate the butt portions 52 of one or more curved felting needles 53 such as that illustrated in FIG. 4. The

butt portion 52 is preferably bent at right angles to a shank portion 54 of which the free extremity 55 forms a trihedron having spaced barbs 56 struck out along each apex of the triangular cross-section. The axis of said shank portion 54 including the free extremity 55 is disposed in a plane within which plane the barbed trihedron extremity of the needle is also preferably curved in a circular conformation having a center of curvature substantially coincident with the axis of the needle rock shaft 50.

For actuating the curved needles 53, a rock arm 60 secured to the needle rock shaft 50 is connected by a link 61 to one end of a lever 62 fulcrumed at 63. A connecting rod 64 pivoted at 65 to the other end of the lever 62 embraces a crank pin 66 carried on a crank pulley 67. The crank pulley 67 is journaled on an eccentric portion 68 of a shaft 69 which is driven by an electric motor 70 by way of a belt 71 which connects a pulley 72 on the motor and a pulley 73 on the shaft 69. The crank pulley 67 is separately driven by means of a belt 74 from a pulley 75 fast on the main drive shaft 12. The speed of rotation imparted to the shaft 69, and hence to the eccentric portion 68, is much greater than that imparted to the crank pulley 67 and may preferably be on the order of 17 revolutions for one revolution of the crank pulley 67. The eccentric, moreover, has sufficient throw as to cause a succession of momentary reversals in the direction of movement of the needle during each needle stroke. The resulting motion of the arcuate needle is therefore a reciprocatory motion impressed with a higher frequency endwise vibration such that each needle stroke comprises a series of overlapping oscillatory increments. It will be understood that the throw of the eccentric portion 68 and the speed of rotation thereof may be selected so as to provide for any desired spacing of the series of reversals in the needle reciprocation as well as to vary the extent to which the needle partakes of retrograde motion during reversal. These factors may thus be chosen to suit the characteristics of the particular fibers being needled.

The curved needles 53 oscillate through apertures 80 and 81 in a pressure plate 82 which may preferably be positioned along with the needle rock shaft 50 selectively toward and away from the supporting surface 11 by conventional biasing mechanism (not shown) by way of pressure rods 83. The curved needles therefore enter and emerge during each reciprocation from the same side or surface of the textile web and by adjustment of the distance of the pressure plate and needle rock shaft from the supporting surface 11 the degree of penetration into the textile web may be regulated.

In order to establish timed operational sequence between work feeding motion and felting needle penetration of the web, the belts 14 and 74 may preferably comprise timing belts formed with clips or lugs and the pulleys 13, 15, 67 and 75 may similarly be formed with lugs or serrations cooperating with the timing belts to maintain a timed relationship such that the textile web will be advanced only while the needles are withdrawn from the web.

In the construction illustrated in FIG. 1, the textile web is maintained flat on the supporting surface 11 during the entire needling process. In FIG. 2 is illustrated a modification in which a textile web indicated at 90 is directed in seriatim over rollers 91, 92, 93, 94 and 95 which rollers are arranged so as to guide the textile web in a sinuous path having, when the web passes about each roller, an arcuate configuration. Disposed one at each side of the rollers are a pair of needle boards or crossheads 96 each carrying straight barbed felting needles 97. The needle boards or crossheads 96 may each be imparted either plain reciprocatory motion in a manner similar to that of the straight needles shown in FIG. 1, or they may be reciprocated in overlapping oscillatory increments as described above. The textile web may be advanced by imparting feed motion to one or more of the rollers while the needles are out of the web. The needles are preferably

disposed each so as to enter and emerge a given side or surface of the textile web during the penetration stroke as the web is guided in an arcuate path about the rollers. As shown in FIG. 2 the use of a pair of needle boards or crosheads one at each side of the web provides for needling of the web from both surfaces thereof.

A further modification is illustrated in FIG. 3 in which needle rock shafts 50, having needle clamps 51 sustaining curved needles 53 in a fashion which may be identical to that illustrated in FIG. 1 and described above, cooperate with a curved surface 100 for supporting a textile web 101. With the arrangement illustrated in FIG. 3 the combined curvature of the needle path of motion and of the textile web positioned opposite to the needles together result in the entry and emergence of the needles from the same side or surface of the textile web.

In FIGS. 2 and 3 the pressure plates have been omitted in the interest of clarity. With certain types of work and particularly where a degree of coherence exists prior to needling sufficient to preserve the stability of the web as it is directed to the needles, a pressure plate may not be required. It will be understood, however, that the inclusion of pressure plates apertured to accommodate passage of the needles as illustrated in FIG. 1 is contemplated in FIGS. 2 and 3.

FIGS. 5 and 6 illustrate diagrammatically that the curved needles may be operated in separate banks with each bank of needles arranged angularly with respect to the other, and with the straight felting needles also arranged in separate banks associated one with each of the banks of curved felting needles.

In FIGS. 5 and 6, two banks of curved felting needles 53A and 53B are illustrated each being sustained in needle clamps 51 carried on needle rock shafts 50 and actuated as illustrated in FIG. 1. As shown in FIG. 5, the direction of motion of needles 53A is indicated by the line A—A, and the direction of motion of the needles 53B by the line B—B. The straight felting needles are arranged in separate banks 31A and 31B but may be sustained in a needle board or croshead 30 actuated as illustrated in FIG. 1. The pressure plate 110 is apertured at 111 to accommodate the straight needles and is apertured at 112 to accommodate the curved needles. A work supporting surface 113 upon which the textile web 114 is disposed may also be apertured as at 115 to accommodate the straight 45 barbed needles 31A and 31B.

In accordance with one method provided by this invention for needling textile webs, the textile web is subjected in seriatim to the action of one or more banks of curved felting needles 53 as illustrated in FIGS. 1, 3, 5 and 6 with the straight felting needles being omitted. Using this method, the path of the needles can be regulated so as to avoid the undersurface of the fabric web. As illustrated in FIG. 8, the novel textile web produced using this method is characterized by the loose or random fiber arrangement of the web being drawn into a series of fiber bundles or fascicles extending in large measure parallel to the plane containing the textile web with the fiber interconcatenation extending to the top surface but avoiding the undersurface. In FIG. 8 the textile layers are shaded for color, fibers of the top layer 120 being concatenated with fibers of the bottom layer 121 in fascicles 125 along the needle paths. The needles may be disposed in angularly arranged banks moving in directions labeled A—A and B—B as illustrated in FIGS. 6 and 7 in which case the fiber fascicles 125 of FIG. 8 will similarly extend in angular and intersecting relation so as to stabilize the resulting fabric web both lengthwise and widthwise.

In accordance with another method provided by this invention, the textile web is subjected first to the action of a bank of straight felting needles 31 penetrating through the web and is subsequently subjected to the action of one or more banks of curved felting needles 53 or to the action of one or more banks of straight felting needles, which as illustrated in FIG. 2, cooperate with curved 75

work supporting surfaces so that the needles each enter and emerge from only one side of the textile web. With this method the textile web is first stabilized thicknesswise by the action of the through-and-through passage of the straight felting needles 31 which results in a partial compaction facilitating transport of the web relatively to the subsequent action of the curved or straight felting needles which enter and emerge from the same side of the web.

Still another method provided by this invention is illustrated in FIGS. 5 and 6 in which the straight through-and-through felting needles and the curved felting needles operate simultaneously upon each individual area on the fabric web.

FIG. 7 illustrates the three dimensional interconcatenation of fibers which is attained when a textile web comprising two fiber layers 130 and 131 is subjected to the action of straight through-and-through felting needles such as 31A or 31B and angularly arranged curved felt-in needles 53A and 53B. The number of needle penetrations per unit area of textile web in each of the three possible directions may be regulated by selection of the rate of feed and the numbers of needles which act in each direction. It will be appreciated that while only one needle acting in each of the three directions is illustrated in FIG. 7, the textile product which will result from the repeated action of such needles or banks of such needles as the web is advanced in regular step-by-step fashion, will comprise a highly coherent web with the fiber fascicles frequently intersecting and located in three substantially perpendicular planes.

Using any of the above methods, the needles whether passing through the textile web or entering and emerging from the same side may be advantageously actuated with overlapping series of oscillatory increments as described in detail hereinbefore. The textile web resulting from such needle actuation is characterized by a greater degree of compaction for a given amount of needling, fewer broken or torn fiber strands and consequently harder and more compact web surfaces, and enhanced fiber concatenation resulting in an increase in strength and durability of the textile web. When the barbed felting needle is imparted a movement in a series of overlapping reciprocatory increments, the barbs once having seized and drawn out fibers in the web, release at least a part of those fibers during the retrograde movements and then seize fresh fibers on the next succeeding increment of the stroke. The result, as illustrated in FIG. 9, is a fascicle of fibers of which at least a portion includes a series of enchain loops 140 of the fiber. Such an enchain fascicle has been found to be inherently stronger and with greater ability to compact the web than a fiber fascicle formed by a continuous reciprocatory motion which merely orients the fibers in the direction of the needle path. Moreover, where curved felting needles are used and partake of a greater length path through the web than comparable straight needles, the overlapping increments of needle reciprocation becomes of particular advantage in reducing fiber breakage. The fibers seized by the needle barbs are not held continuously as they are with conventional plain reciprocation until either the fiber breaks or the penetrating stroke of the needle is completed; but instead the degree of fiber loop formation may be controlled. As a result not only can greater degree of compaction and strength be attained than heretofore, but fibers which had heretofore been considered too brittle or too inextensible for needling may now be felted successfully using this mode of needle actuation.

Having set forth the nature of this invention what is claimed herein is:

1. A felting needle having a butt adapted to be secured in a needle clamp, a shank extending from said butt and having an axis disposed in a plane, said shank formed with a tapered free extremity which is curved in a circular conformation, and spaced barbs struck out along said free extremity.

2. A felting needle having a butt adapted to be secured in a needle clamp, a shank extending from said butt and having an axis disposed in a plane, said shank formed with a trihedron shaped free extremity curved in circular conformation, and spaced barbs struck out along at least one apex of said trihedron.

3. Mechanism for needling textile webs comprising means providing a work supporting surface for a textile web, a needle rock shaft journaled at one side of said work supporting surface, a barbed felting needle carried by said needle rock shaft and formed with a circularly curved blade having a center of curvature substantially coincident with the axis of said needle rock shaft, means for oscillating said needle rock shaft to effect work penetration of a textile web on said work supporting surface with entry and emergence of said curved felting needle on the same surface of said textile web during each needle penetration, and means for advancing said textile web along said work supporting surface between successive needle penetrations.

4. Mechanism for needling textile webs comprising means providing a work supporting surface for a textile web, a barbed felting needle, means supporting said barbed felting needle for endwise work penetrating reciprocatory movement substantially within a reference plane relatively to said work supporting surface, said work supporting surface and said needle path being arcuately curved one relatively to the other about an axis substantially perpendicular to said reference plane of needle reciprocation so as to effect on each needle penetration entry and emergence of said felting needle on the same surface of a textile web on said work supporting surface, and means for advancing said textile web along said work supporting surface between successive needle penetrations.

5. Mechanism for needling textile webs comprising means providing a work supporting surface for a textile web, a straight felting needle, means shiftably supporting said straight felting needle for endwise reciprocatory work penetrating movement substantially perpendicular to said work supporting surface, a needle rock shaft journaled at one side of said work supporting surface, a circularly curved felting needle, means supporting said curved felting needle for oscillatory movement about an axis substantially coincident with the center of curvature thereof for work penetrating movement entering and emerging from the same side of a textile web carried on said work supporting surface, means for imparting work penetrating movement simultaneously to said supporting means for said straight and said curved felting needles, and means for advancing said textile web along said work supporting surface between successive needle penetrations.

6. In a mechanism for needling textile webs and including a work support for a textile web and an endwise reciprocating barbed felting needle, means for reciprocating said needle comprising a primary actuating means for imparting to said needle substantially the total amplitude of reciprocatory motion thereof, and a secondary actuating means operable simultaneously with said primary actuating means for imparting to said needle a small fraction of the total amplitude of reciprocatory motion thereof, and means for operating said secondary actuating means at a frequency sufficiently higher than that of said primary actuating means so as to effect reciprocation of a said needle in a series of overlapping reciprocatory increments.

7. In a mechanism for needling textile webs and including a work support for a textile web and an endwise reciprocating barbed felting needle, a primary actuating means for imparting to said needle an amplitude of reciprocatory motion, a secondary actuating means operable simultaneously with said primary actuating means for imparting to said needle a smaller amplitude of reciprocatory movement than said primary actuating means at a higher frequency than said primary actuating means.

8. In a mechanism for needling textile webs and including a work support for a textile web and an endwise recip-

rocatory barbed felting needle, crank means for imparting endwise reciprocatory movement to said barbed felting needle, a rotary actuator operatively connected to drive said crank means, an eccentric bearing sustaining said 5 rotary actuator, and means for imparting turning movement to said eccentric during rotation of said actuator and at an angular speed sufficiently greater than that of said actuator so as to effect reciprocation of said needle in a series of overlapping reciprocatory increments.

10. The method of concatenating the fibers of a textile fiber web by the action of a barbed felting needle comprising imparting endwise reciprocatory movement in alternating fiber web penetrating and withdrawing strokes to a barbed felting needle, positioning the textile web relatively to the path of endwise reciprocation of said barbed felting needle for entry and emergence of the barbed felting needle on the same side of the textile web during the penetration stroke of the needle reciprocation, and shifting a fresh area of said textile web into said position during 15 each withdrawal stroke of the needle reciprocation.

10. The method of concatenating the fibers of a textile fiber web comprising sustaining a textile web substantially parallel to a reference plane, alternately penetrating and withdrawing from said textile web a circularly curved 25 barbed felting needle oscillatable about an axis which is substantially coincident with the center of curvature of said needle and which is disposed parallel to said reference plane, and shifting the position of said textile web in said reference plane during periods of withdrawal of said 30 needle from said textile web.

11. The method of concatenating the fibers of a textile fiber web by the action of a barbed felting needle comprising imparting endwise reciprocatory movement in alternating fiber web penetrating and withdrawing strokes 35 to a barbed felting needle, positioning the textile web relatively to the path of endwise reciprocation of a barbed felting needle for entry and emergence of the barbed felting needle on the same side of the textile web during the penetration stroke of the needle reciprocation, arranging 40 said path of needle reciprocation to avoid completely the opposite side of said textile web, and shifting a fresh area of said textile web into said position during each withdrawal stroke of the needle reciprocation.

12. The method of concatenating the fibers of a textile fiber web comprising, sustaining a textile web substantially 45 parallel to a reference plane, penetrating and withdrawing from said textile web at least two circularly curved barbed felting needles oscillatable about axes which are substantially coincident each with the center of curvature of a respective one of said needles and angularly arranged 50 relatively to each other in a plane parallel to said reference plane, and shifting the position of said textile web in said reference plane during periods of withdrawal of said needles from said textile web.

13. The method of effecting three dimensional fiber concatenation of a textile fiber web comprising, sustaining a textile web substantially parallel to a reference plane, penetrating and withdrawing a barbed felting needle in a path through said textile web substantially perpendicular 60 to said reference plane, penetrating and withdrawing from said textile web at least two circularly curved barbed felting needles oscillatable about axes which are substantially coincident each with the center of curvature of a respective one of said needles and angularly arranged relatively to 65 each other in a plane parallel to said reference plane, and shifting the position of said textile web in said reference plane during periods of withdrawal of said needles from said textile web.

14. The method of concatenating the fibers of a textile fiber web comprising positioning a textile web relatively 70 to the path of endwise reciprocation of a barbed felting needle, imparting to said needle an endwise web penetrating and withdrawing reciprocation impressed with a higher frequency endwise vibration such that each needle stroke 75 comprises a series of overlapping reciprocatory incre-

ments, and shifting the position of said textile web during periods of withdrawal of said needle from said textile web.

15. The method of concatenating the fibers of a textile fiber web comprising sustaining a textile web substantially parallel to a reference plane, alternately penetrating and withdrawing from said textile web a circularly curved barbed felting needle oscillatable about an axis which is substantially coincident with the center of curvature of said needle and which is disposed parallel to said reference plane, imparting to said needle a primary endwise oscillation impressed with a higher frequency secondary endwise vibration such that each needle stroke comprises a

series of overlapping oscillatory increments, and shifting the position of said textile web in said reference plane during periods of withdrawal of said needle from said textile web.
